THEFT-PREVENTING ARRANGEMENT FOR
MOTORCARS

Honorio Vizcaino Hueso, Mexico City, Mexico

Application September 6, 1951, Serial No. 245,352
In Mexico December 1, 1950

5 Claims. (Cl. 340—63)

1

The present invention relates to a theft-preventing arrangement for motorcars, and more particularly to the arrangement of a brake-actuating manually operable device in the closable trunk compartment of a motorcar.

It is the object of the present invention to provide an arrangement by which a motorcar is protected from being stolen.

It is a further object of the present invention to provide a brake-actuating device in the trunk compartment of a motorcar so that the motorcar may be braked while parked, the brake being releasable only after unlocking of the trunk compartment.

It is another object of the present invention to provide electric alarm means which are actuated when a metal tool is inserted under the door of the trunk compartment for the purpose of forcing the same open.

With these objects in view the present invention mainly consists in a manually-operable brake-actuating member mounted in a closable trunk compartment of a motorcar movably between a braking position and a releasing position, motion-transmitting means movably mounted on the body of the motorcar and secured at one end thereof to the brake and at the other end thereof to the manually operated brake-actuating member, and locking means mounted also in the trunk compartment for arresting the manually operated brake-actuating member in braking position, so that when the brake-actuating member is in braking position, and the trunk compartment is closed, moving of the motorcar by unauthorized persons is prevented.

In accordance with a preferred embodiment the present invention mainly consists of a closable trunk compartment in the motor car provided with a door, means insulating the door from the body of the motorcar, a supporting base plate fixedly secured to the inside of the trunk compartment, a brake-actuating disc member rotatably mounted on the base plate and provided with a rack portion on its perimeter, manually operable lever means fixedly secured to the disc member for manually turning the same between a braking position and a releasing position, motion-transmitting cable means movably mounted on the body of the motor car and secured at one end thereof to the brake and at the other end thereof to the perimeter of the brake-actuating disc so as to be wound up on the same when the brake-actuating disc member is turned by said manually operable lever means whereby the brake is actuated when the brake-

2

actuating disc is turned into braking position and released when the brake-actuating disc is turned into releasing position, spring-loaded pawl means mounted in the trunk compartment on the base plate and adapted to engage the rack portion on the perimeter of the brake-actuating disc member when the brake-actuating disc member is in braking position, and adapted to be manually released so that the brake-actuating disc member may be turned into releasing position by the manually operable lever means whereby moving of the motor car is prevented when the brake-actuating disc member is in braking position and the trunk compartment is closed, electric alarm means including a circuit connected to the electric system of the motor car, and contact means in the circuit of the electric alarm means connected to the body of the motor car on one hand and to the door of the trunk compartment of the motor car on the other hand so as to cause actuation of the electric alarm means when a metal tool is inserted between the door of the trunk compartment and the body.

25 The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

35 Fig. 1 is a schematic perspective view of the trunk compartment of a motor car provided with a theft-preventing arrangement according to the present invention;

Fig. 2 is a rear view of the motor car;

40 Fig. 3 is a perspective view of the driver's seat of a motor car, illustrating a further protective device;

Fig. 4 is a view similar to Fig. 3; and

Fig. 5 is a wiring diagram of the theft-preventing arrangement.

45 Referring now to the drawings, Fig. 1 shows a supporting base plate 1 secured to the inside of the trunk compartment of a motor car. A disc member 2 is rotatably mounted on a supporting base plate 1 secured by screws to the inside of the trunk compartment of the car. The disc member 2 is provided on approximately one third of its perimeter with a rack portion 2' engaged by a spring-loaded pawl 4. A steel cable 3 guided in a sleeve 5 is fixedly secured, preferably

welded, to the perimeter of the disc member 2 so as to be wound upon the smooth perimeter of the same, which may be provided with a groove, when the same is rotated by the manually operated lever 2'', which may be welded to disc member 2. The cable 3, 5 passes through a hole 6 in the bottom of a trunk compartment to the under side of the motor car and is secured thereto by clamps 7. The end of cable 3 is connected at 16 to the center of a steel cable 8 extending transversely and being secured at 15, 15 to cables 9a, 9a leading to the brakes of the motor car. All fastening screws are preferably secured by welding.

The operation of the arrangement is as follows:

When the manually operable lever 2'' is pulled backwards, the disc member is turned, and the steel cable is wound up on the same whereby the hand brake is actuated. The pawl member 4 engages the rack portion of the disc member in this braking position. The trunk compartment is now locked and the motor car cannot be moved by anybody without first opening the trunk compartment. Since the locked trunk compartment can only forcibly be opened by an unauthorized person, such action would require time and would attract attention, whereby theft of the motor car is prevented. When the pawl 4 is manually retracted by the operator of the car after the trunk compartment has been unlocked, the rotatable disc member is placed in a releasing position so that the car may be used again.

To provide even safer protection of the car, the trunk compartment may be provided with an auxiliary device comprising an electric alarm siren 10 fixedly mounted in the interior of the trunk compartment, or under the hood of the car. An insulated electric cable 13 connects the siren with the door 17 of the trunk compartment which is insulated from trunk compartment and the body of the car. Another electric cable 11 passes through a hole 12 in the bottom of the trunk compartment and connects the siren to the electric system of the motor car. Since the door 20 of the trunk compartment is insulated from the body of the car 21, inserting of a metal tool 22, Fig. 2, will result in closing the circuit of the siren and cause sounding of an alarm. Consequently, any unauthorized person who attempts to open the locked door of the trunk compartment by force in order to release the above-described theft-preventing brake-actuating arrangement, would sound the siren and attract attention. As can be seen from the upper portion of Fig. 5, the electric current flows from the battery 23 of the car through cable 11, siren 10, cable 13 to the door 20 of the trunk compartment, and further through the portions 21 of the body of the car back to the grounded terminal of the battery 23, if the insulation 21' is short-circuited by a metal tool inserted between door 20 and the body of the car in the manner shown in Fig. 2.

An additional safety device is contemplated for preventing theft of articles left on the seat of the car through the window. Fig. 4 shows a cable F provided with a sleeve-shaped metal contact D which is supported in a support E adjacent to a pivoted window. The end of the sleeve-shaped contact D abuts against the glass panel of the window without contacting the metal frame thereof. Cable F is sufficiently long to be attached to the window frame and to be withdrawn therefrom when its use is not required, in which case it is suspended below the dashboard in such manner that the sleeve-shaped contact does not

contact any metal parts of the car. The portion of the sleeve-shaped contact which is supported by the support E is insulated.

Cable A is an extension of cable F and is connected into the circuit of the alarm siren so that in the event that thieves attempt to force open the window by exerting a strong pressure on the smaller portion of the window C causing the same to pivot about its shaft I, the metal frame C1 of the window contacts the sleeve-shaped contact and actuates the alarm siren. As is clearly shown in the lower portion of Fig. 5, electric current flows from battery 23, cable 11, siren 10, cable A, cable F, the metal contact D, the frame of the window C', pivot pin I, and through the body of the car back to the grounded terminal of the battery 23 when the window is pivoted to the position shown in full lines in Fig. 5, and the contact E, D' is placed in the support E, the portion E' being made of insulating material.

Similar protective arrangements may be provided for the other windows of the car.

It will be understood that each of the elements described above, or two or more together, may also find a useful application in other types of theft-preventing arrangements for motor cars differing from the types described above.

While the invention has been illustrated and described as embodied in a theft-preventing arrangement comprising a brake-actuating device in the trunk compartment of a motor car and electric alarm means actuated by insertion of a tool under the door of a trunk compartment, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention, and, therefore, such adaptations should and are intended to be comprehended within the meaning and range of equivalence of the following claims.

What is claimed as new and desired to be secured by Letters Patent is:

1. In a motor car including a body and a brake, in combination, a closable trunk compartment located in the body of the motor car; a manually operated brake-actuating member mounted in said trunk compartment movably between a braking position and a releasing position; motion-transmitting means movably mounted on the body of said motor car and secured at one end thereof to the brake and at the other end thereof to said manually operated brake-actuating member; and locking means mounted also in said trunk compartment for arresting said manually operated brake-actuating member in braking position, so that when said brake-actuating member is in braking position, and said trunk compartment is closed, moving of the motor car by unauthorized persons is prevented.

2. In a motor car including a body containing a trunk compartment and a brake, a theft-preventing protective arrangement, comprising in combination, a manually operated brake-actuating member mounted in the trunk compartment movably between a braking position and a releasing position; motion-transmitting means movably mounted on the body of said motor car and se-

cured at one end thereof to the brake and at the other end thereof to said manually operated brake-actuating member; and locking means mounted also in the trunk compartment for arresting said manually operated brake-actuating member in braking position, so that when said brake-actuating member is in braking position, and the trunk compartment is closed, moving of the motor car by unauthorized persons is prevented.

3. In a motor car including a body and a brake, in combination, a closable trunk compartment in the body of the motor car; a supporting base plate fixedly secured to the inside of said trunk compartment; a brake-actuating disc member rotatably mounted on said base plate and provided with a rack portion on its perimeter; manually operable lever means fixedly secured to said disc member for manually turning the same between a braking position and a releasing position; motion - transmitting cable means movably mounted on the body of the motor car and secured at one end thereof to the brake and at the other end thereof to the perimeter of said brake-actuating disc so as to be wound up on the same when said brake-actuating disc member is turned by said manually operable lever means whereby the brake is actuated when said brake-actuating disc is turned into braking position and released when said brake-actuating disc is turned into releasing position; and spring-loaded pawl means mounted in said trunk compartment on said base plate and adapted to engage said rack portion on the perimeter of said brake-actuating disc member when said brake-actuating disc member is in braking position, and adapted to be manually released so that the brake-actuating disc member may be turned into releasing position by said manually operable lever means whereby moving of the motor car is prevented when said brake-actuating disc member is in braking position and said trunk compartment is closed.

4. In a motor car including a body and a brake, in combination, a closable trunk compartment in the body of the motor car; a supporting base plate fixedly secured to the inside of said trunk compartment; a brake-actuating disc member rotatably mounted on said base plate and provided with a rack portion on its perimeter; manually operable lever means fixedly secured to said disc member for manually turning the same between a braking position and a releasing position; movable motion-transmitting cable means secured at one end thereof to the brake and at the other end thereof to the perimeter of said brake-actuating disc so as to be wound up on the same when said brake-actuating disc member is turned by said manually operable lever means whereby the brake is actuated when said brake-actuating disc is turned into braking position and released when

5 said brake-actuating disc is turned into releasing position, said motion-transmitting cable means passing through a hole in said trunk compartment to the under side of said body; guiding sleeve
means on said cable means fixedly secured to the under side of the body of the motor car for guiding said cable means; and spring-loaded pawl
means mounted in said trunk compartment on said base plate and adapted to engage said rack
10 portion on the perimeter of said brake-actuating disc member when said brake-actuating disc member is in braking position, and adapted to be manually released so that the brake-actuating disc member may be turned into releasing position
15 by said manually operable lever means whereby moving of the motor car is prevented when said brake-actuating disc member is in braking position and said trunk compartment is closed.
20 5. In a motor car including a body and a brake, in combination, a closable trunk compartment in the body of the motor car; a supporting base plate fixedly secured to the inside of said trunk compartment; a brake-actuating disc member rotatably mounted on said base plate and provided with a rack portion on its perimeter; manually operable lever means welded to said disc member for manually turning the same between a braking position and a releasing position; motion-transmitting cable means movably mounted on the body of the motor car and welded at one end thereof to the brake and at the other end thereof to the perimeter of said brake-actuating disc so as to be wound up on the same when said brake-actuating disc member is turned by said manually operable lever means whereby the brake is actuated when said brake-actuating disc is turned into braking position and released when said brake-actuating disc is turned into releasing position; and spring-loaded pawl means mounted in said trunk compartment on said base plate and adapted to engage said rack portion on the perimeter of said brake-actuating disc member when said brake-actuating disc member is in braking position, and adapted to be manually released so that the brake-actuating disc member may be turned into releasing position by said manually operable lever means whereby moving of the motor car is prevented when said brake-actuating disc member is in braking position and said trunk compartment is closed.
